UNITED STATES PATENT OFFICE.

JOHN E. GARDNER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed February 2, 1921, Serial No. 441,875. Renewed September 17, 1926.

The present invention relates in general to automatic telephone systems, but is more particularly concerned with systems of the type usually installed in small automatic exchanges, such systems being commonly known as private automatic exchanges. Exchanges of this character are largely in use in manufacturing or mercantile establishments of various kinds for providing local service between the different departments. The service requirements of such a system are different from those in a public automatic exchange and it is often necessary to provide many features which are not generally used in a larger system. The present invention is concerned particularly with one of these features, a scheme that is known as conference calling. This is an arrangement whereby three or more telephone lines in a private automatic exchange may be telephonically connected together at the same time.

The present invention contemplates a novel and improved means of effecting the above result, together with other features which will fully appear hereinafter. In order to simplify the description the invention has been shown applied to an isolated private automatic exchange, but it will be readily apparent that it is not limited to this use.

The drawings accompanying this specification and comprising Figs. 1 to 4, inclusive, show by means of the usual circuit diagrams sufficient of the apparatus in a private automatic exchange to enable the invention to be explained and understood. Figure 1 shows two automatic substations A and A', with their associated individual line switches C and C'; Figs. 2 and 4 show two automatic connector switches which are accessible to the subscribers' individual line switches, and which in turn have access to the subscribers' lines; while Fig. 3 shows a special rotary line switch which has access to the connector switches in common with the subscribers' individual line switches, and which is accessible to the connector switches by way of a so-called "conference number."

Referring now to Fig. 1, two automatic substations A and A' are shown having rotary line switches C and C' of the usual construction individual thereto. These line switches in common with a plurality of similar line switches have access to trunk lines terminating to local connector switches, two of these being shown terminating in con-

nectors H and H', Figs. 2 and 4. These connectors are of the Strowger type and have the usual set of 100 bank contacts arranged in ten rows or levels. On all levels the switch H has access to local subscribers' lines and functions as an ordinary connector switch. On certain numbers, in this case the conference number 30, the connector H switches through in the same manner as a selector but at this time it does not have the trunk selecting feature. All the bank contacts in the connector H are multiplied in the usual manner into all the other local connector switches, this multiple being illustrated in the drawings between the switches H and H'.

The multiple leading from the conference number 30 terminates in the switch F. This is a rotary switch having a trunk selecting function similar to a rotary line switch besides several other features which will appear fully later. The trunks accessible to the line switches C and C' are also accessible to the switch F but the trunks in themselves differ inasmuch as they consist of four conductors instead of three. It will be noted that the wipers of the line switches C and C' are not shown associated with the same trunk line. They have not been so shown for the reason that these switches have no normal position and their wipers might be in engagement with any trunk line.

Having briefly described the construction of the apparatus used in the system a detailed description of its operation will now be given. For this purpose it will be assumed that the subscriber at substation A desires to hold a conference. He will therefore remove his receiver and operate his calling device for the usual local number of the first subscriber desired in the conference prefixing the conference number 30. When the receiver is removed at substation A a circuit is completed over the line conductors 11 and 12 for the line relay 16 of the line switch C. Upon energizing, the line relay 16 closes at its armature 21 a circuit which includes the switching relay 15 and the stepping magnet 17 in series, and at its armature 20 connects the test wiper 28 to the above circuit at a point midway between the switching relay and the said stepping magnet. The operation now depends upon whether the trunk line with which the wipers of the line switch C are associated is or

2

is not busy. If the trunk line is busy, the test contact with which the test wiper 28 is in engagement will be grounded, and as a result the switching relay 15 will be short circuited and the stepping magnet 17, being supplied with direct ground by way of the test wiper will operate as a buzzer to advance the switch wipers step by step in search of an idle trunk line. It may be assumed, however, that when the call is initiated the wipers of the line switch C are standing upon the bank contacts shown in the drawings, and it may be assumed further that the trunk line extending from these bank contacts is idle. Under these circumstances the test contact 33 will have no ground potential upon it and when the receiver is removed the energization of the line relay 16 is followed immediately by the energization of the switching relay 15. It may be stated at this point that the switching relay is of comparatively high resistance so as to prevent the operation of the stepping magnet 17 at this time. As a result of the energization of the switching relay 15 the line conductors 11 and 12 are disconnected from the line relay 16 and from ground, respectively, and are extended by way of armatures 23 and 24 and their front contacts, wipers 27 and 29, bank contacts 32 and 34, conductors 53 and 55, conductors 71 and 77, normally closed springs controlled by relay 90, normally closed springs controlled by the relay 100, normally closed springs controlled by relay 101 and thence through the upper and lower windings of the line relay 103 of the connector H to battery and ground, respectively.

When the calling line is extended to the switch H as above described the line relay 103 is energized over the line circuit in the usual manner and completes the circuit of the slow acting release relay 104. Upon energizing, the latter relay prepares the circuits of the switch H for operation at armature 134 and at armature 132 connects ground to the release trunk conductor 73 thereby establishing a holding circuit for the line switch C which extends by way of the conductor 54, test contact 33, test wiper 28, armature 25 and its front contact, winding of the switching relay 15 and the winding of the stepping magnet 17 to battery. The above circuit is completed before the slow acting line relay 16 has had time to deenergize and serves to maintain the switching relay 15 energized throughout the connection. Ground is also extended by way of the private normal conductor 66 to multiply connected test contacts in the banks of the local connector switches which have access to the line of substation A whereby the said line is protected from intrusion in the well known manner.

65 The calling subscriber may now operate

his calling device in accordance with the first digit of the conference number namely 3. Three interruptions are thereby produced in the line circuit of the line relay 103 which deenergizes a corresponding number of times 70 in response thereto. At each retraction of its armature 129 a circuit is completed extending from ground G' by way of armature 129 and its back contact, armature 125 and its back contact, armature 116 and its back contact, armature 134 and its front contact, off normal springs 156 and 157, winding of the series relay 106 and thence through the winding of the vertical magnet 110 to battery. The above is the circuit over which 80 the first impulse to the vertical magnet is sent. Upon the first vertical step of the shaft the off normal springs are shifted and the circuit for the vertical magnet is then completed over a new path which is the 85 same as the one previously traced except that it includes the off normal springs 156 and 158 and armature 141 and its front contact, relay 106 now being in an operated position. Magnet 110 operates to raise the 90 switch wipers 160-162, inclusive, step by step until they are placed opposite the third level of bank contacts. Relay 106 is energized in series with the vertical magnet and maintains its armature attracted throughout the vertical operation of the switch and at the termination of the vertical movement deenergizes and transfers the operating circuit to the rotary magnet 111.

The calling subscriber may now operate 100 his calling device in accordance with the last digit of the conference number namely 0. Ten interruptions are thereby produced in the line circuit of the relay 103 which deenergizes a corresponding number of times 105 each time sending an impulse to the rotary magnet 111 over the following circuit: Ground G', armature 129 and its back contact, armature 125 and its back contact, armature 116 and its back contact, armature 134 and its front contact, off normal springs 156 and 158, armature 141 and its back contact, armature 148 and its back contact, winding of the slow acting series relay 107, back contact and armature 153, and thence through 110 the winding of the rotary magnet 111 to battery. Magnet 111 operates to rotate the wipers 160-162, inclusive, into engagement with the set of contacts associated with the conference number 30, which we will assume, are the bank contacts 165-167, inclusive. Relay 115 107 is energized in series with the rotary magnet and, being a slow acting relay, maintains its armature attracted throughout the rotation of the switch, operating to connect the test wiper 161 to the test relay 108. When the switch wipers are rotated into engagement with the conference number the spring 120 is shifted into engagement with 120 the spring 121 by the operation of the cam 125 130

on the switch shaft. However, this operation will have no effect at this time. The further operation of the connector H depends upon whether or not the conference number is busy. If busy, a ground potential will be present on the test contact 166 engaged by the test wiper 161. A circuit is thereby completed extending from the said grounded test contact, by way of the test wiper 161, armature 143 and its front contact and through the winding of the test relay 108 to battery. Upon energizing, the relay 108 establishes a locking circuit for itself at armature 147 and at armature 149 places the busy tone from the busy machine T on the calling subscriber's line. This tone will inform the subscriber at substation A that the conference number is busy at this time and he will therefore, hang up his receiver initiating the release of the switches C and H in a manner to be hereinafter described.

However, it will be assumed in the present case that the conference number was idle when connection thereto was attempted. Under these circumstances no ground will be present on test contact 166 and there will be no circuit for the test relay 108. Following the deenergization of the slow acting relay 107, a circuit is completed extending from ground on release trunk conductor 73 by way of armature 147 and its back contact, a lower winding of the switching relay 109, back contact and armature 143, test wiper 161, test contact 166, and through the resistance R to battery. Relay 109 energizes over this circuit and upon operating, establishes a locking circuit for itself at armature 152, and at armature 154 connects the lower talking conductor to the wiper 162. Another circuit completed by the energization of relay 109 extends from ground on release trunk conductor 73 by way of front contact and armature 152, springs 120 and 121, through the winding of relay 100 to battery. Upon energizing, relay 100 disconnects the line conductors 11 and 12 of the substation A from the upper and lower windings of the line relay 103 and extends them by way of armatures 115 and 118 and their front contacts, wipers 160 and 162, bank contacts 165 and 167, conductors 186 and 188, conductor 259 which extends through the upper winding of the polarized relay 201, armature 215 and its back contact, and through the winding of the line relay 203 to battery and conductor 257 which extends by way of armature 219 and its back contact to ground.

The line relay 203 of the special rotary switch F is therefore energized over the line circuit and upon operating places ground on the release trunk conductor 258 thereby establishing a holding circuit which extends by way of conductor 187, test contact 166, test wiper 161, armature 151 and its front

contact, front contact and armature 152 where it divides one circuit extending through the winding of the switching relay 109 to battery and the other by way of springs 120 and 121 through the winding of relay 100 to battery. This ground also extends over the release trunk conductor 73 to the line switch C. These circuits serve to maintain the switches C and H in their operated position. Relay 203 also completes at 75

its armature 224 a circuit which includes the switching relay 202 and the stepping magnet 207 in series and at armature 223 connects the test wiper 236 to the above circuit at a point midway between the switching relay and the said stepping magnet. The operation of the switch F now depends upon whether the trunk line with which the wipers 235-238, inclusive, are associated, is or is not busy. If busy, a ground potential will be present on the test contact 241, the switching relay, being now short circuited, will not energize and the stepping magnet 207 being supplied with direct ground by way of said test wiper operates as a buzzer to advance the switch wipers step by step in search of an idle trunk line. However, it will be assumed in the present case that the trunk line terminating in the bank contacts 240 to 243, inclusive, with which the wipers of the switch F are now associated is idle and it will be assumed furthermore that the switch wipers were associated with it upon the switch being seized.

Under these circumstances, following the energization of the line relay 203, the switching relay 202 is energized immediately afterwards. It may be stated at this point that the switching relay 202 is of very high resistance so as to prevent the operation of the stepping magnet 207 at this time. By the 100 operation of the switching relay 202 the line conductors of the calling substation are disconnected from the winding of the line relay 203 and from ground, respectively, and are extended by way of armatures 215 and 219 110

and their front contacts, wipers 235 and 238, bank contacts 240 and 243, trunk conductors 250 and 256, normally closed springs controlled by relay 265, normally closed springs controlled by relay 275, and then through the upper and lower windings of the line relay 278 of the connector H'. Relay 278 energizes over the line circuit and completes a circuit of the slow acting release relay 279. Upon energizing, the latter relay prepares 115 the circuits of the connector H' for operation at armature 312 and at armature 310 places ground on the release trunk conductor 253 thereby establishing a holding circuit which extends by way of test contact 241, test wiper 236, armature 217 and its front contact, through the winding of the switching relay 202, armature 212 and its back contact, back contact and armature 225 and thence through the winding of the stepping magnet 207 120

125

130

to battery. It will be understood that this circuit is completed before the line relay 203 has had time to deenergize. Relay 202 upon operating also places ground on the release trunk conductor 258 and at the same time energizes the polarizing winding of the polarized relay 201. Before proceeding further, it will be necessary to note certain adjustments of the relay 202 which are made to 10 secure correct operation. The armatures 215 and 219 are adjusted to engage their front contacts before the armature 218 engages its front contact. This adjustment is made so as to prevent the energization of the 15 slow acting relay 205 at this time, the relay 204 energizing before it and breaking its energizing circuit at armature 228. The polarized relay 201 is so adjusted that it will not attract its armatures unless current flows 20 in the same direction in both of its windings. The necessary adjustments are all easily made and cause no difficulty whatever in practice. It will be noticed that the relay 204 is included in one side of the line circuit 25 and it will therefore energize in series with the line relay 278.

The calling subscriber may now operate his calling device in accordance with the first digit of the desired subscriber's number. A series of interruptions are thereby produced in the circuit of the line relay 278 which deenergizes in response thereto and sends a corresponding series of impulses to the vertical magnet 295. Magnet 295 operates to raise the switch wipers 350-352, inclusive, step by step until they are placed opposite the level of bank contacts in which is located the terminals of the desired subscriber's line. The slow acting relay 281 in 40 the switch H' which is energized in series with the vertical magnet maintains its armature attracted throughout the vertical operation of the switch and at the termination of the vertical movement deenergizes transferring the operating circuit to the rotary magnet 294.

The operation of the various relays in the switch F in response to this digit will now be described. The relay 204 in the switch 50 operates in series with the line relay 278 of the selected connector and completes a circuit extending from ground G¹⁰, by way of armature 218 and its front contact, armature 228 and its back contact, through the winding of the slow acting relay 205 to battery. This latter relay will now energize in response to this series of impulses placing ground on the front contact of armature 229 at armature 231. An impulse of current 55 will then be sent over a circuit extending from ground G¹¹ by way of front contact and armature 231, front contact and armature 229, and thence through the winding of the slow acting relay 200 to battery. Upon 60 energizing, this latter relay establishes a

locking circuit for itself at armature 211 and at armature 210 places ground on the release trunk conductor 258.

The calling subscriber may now operate his calling device in accordance with the last 70 digit of the desired subscriber's number thereby producing a series of interruptions in the line relay 278 which deenergizes a corresponding number of times in response thereto. At each retraction of its armature 75 307 an impulse of current is sent to the rotary magnet 294 in series with the slow acting relay 282. Magnet 294 operates to rotate the wipers 350-352, inclusive, into engagement with the set of contacts associated 80 with the desired subscriber's line.

To proceed with the operation of the connector H', the slow acting relay 282 is energized in series with the rotary magnet, maintains its armature attracted throughout 85 the rotation of the switch, and operates to connect the test wiper 351 to the test relay 283. The further operation of the connector H' depends upon whether or not the line of 90 the desired subscriber is or is not busy.

The relay 204 in the switch F operates in response to the second digit of the called subscriber's number and as before completes the circuit of the slow acting relay 205. However the operation of these various relays in this switch is without function at 95 this time and may be disregarded.

If busy, a ground potential will be present on the test contact engaged by the test wiper 351. A circuit is thereby completed from the said grounded test contact by way of the said test wiper 351, armature 322 and its front contact, and through the winding of the test relay 283 to battery. Upon energizing, relay 283 establishes a locking circuit for itself at armature 326 and at armature 328 connects the busy tone from the busy machine T' on the lower talking conductor which extends back to the calling substation A by way of the switches F, H, and C. The calling subscriber upon hearing this tone will know that the desired subscriber's line is inaccessible for the time being, and he will therefore replace his receiver upon the switchhook thus breaking the line circuit of relay 278 which deenergizes. Upon deenergizing, relay 278 completes a circuit for the release magnet 293 of the switch H' over a path extending from ground by way of armature 307 and its back contact, armature 302 and its back contact, armature 290 and its back contact, armature 312 and its back contact, off normal springs 313 and thence through the winding of the release magnet 293 to battery. Magnet 293 operates to restore the switch H' to normal. When relay 278 deenergizes the relay 204 in the switch F which is included in the line circuit also deenergizes and its operation will have no effect at this time. It 100 105 110 115 120 125 130

will be noticed that the slow acting relay 200 is maintained energized over its locking circuit and holds ground on the release trunk conductor 258 preventing the release 5 of the switches H and C.

The calling subscriber may now do one of two things, wait and call the subscriber at the desired substation later or proceed to call the other parties desired in the conference. In the former case it will be necessary to release the connections now being held up, that is, the switches H and C. In order to do this the subscriber, having replaced his receiver to bring about the release 10 of the connector H', as explained above, will simply remove his receiver and then replace it again. When the receiver is removed at substation A, the line relay 203 of the rotary switch F will energize and break 15 the locking circuit of the relay 200 at armature 224 which relay will deenergize after a short interval removing ground from the release trunk conductor 258. However, this will have no effect if the calling subscriber 20 holds the line as the relays 203 and 202 in turn replace ground thereon and the trunk selecting operation of the rotary switch will take place in a manner hereinbefore explained. When the calling subscriber hangs 25 up the receiver, since relay 200 is no longer locked up, this ground is removed from the release trunk conductor 258 and all the switches are restored to normal in a manner hereinafter described.

In the latter case the calling subscriber after removing his receiver will proceed to operate his calling device in accordance with the digits of the next subscriber's number. It is assumed that the connector H' was 30 selected by the rotary switch. When the calling device is operated for the first digit of the second subscriber's number the line relay 278 responds to the interruptions of its line circuit to control the operation of the 35 vertical magnet 295. Magnet 295 operates as before to raise the switch wipers 350-352, inclusive, step by step until they are placed opposite the level of bank contacts in which the set of contacts associated with the desired 40 second subscriber's line is located. As before, the relay 204 in the switch F operates to complete the circuit of the slow acting relay 200 which energizes and establishes a locking circuit for itself at armature 211 and places ground on the release trunk conductor 258 at armature 210.

The calling subscriber may now operate his calling device in accordance with the last digit of the subscriber's number again producing a series of interruptions in the circuit of the line relay 278 which operates to control the operation of the rotary magnet 294 in stepping the switch wipers into engagement with the set of bank contacts 360- 45 362, inclusive, associated with the line of the

subscriber at substation A'. As before, the slow acting relay 282 is energized in series with the rotary magnet 294. It will be assumed in the present case that the desired subscriber's line is idle. Under these conditions no ground will be present on the test contact engaged by the test wiper 351 and there will be no circuit for the test relay 283. Upon the deenergization of the slow acting relay 282 a circuit is completed extending from ground on release trunk conductor 253 by way of the armature 326 and its back contact, lower winding of the switching relay 284, back contact and armature 322, test wiper 351, test contact 361 of the desired subscriber's line engaged by the said test wiper 351 and thence over the private normal conductor 181, conductor 69, through the winding of the switching relay 43 and through the winding of the stepping magnet 45 of the line switch C' associated with the line of the called subscriber at substation A' to battery. The switching relays 284 and 43 energize over this circuit. However, due to a mechanical interlocking device controlled by the armature of the line relay 44 the switching relay 43 only attracts its armatures part way, enough to disconnect the line conductors of the substation A' from their normal battery and ground connections 50 in the line switch C. Relay 284, upon operating, establishes a locking circuit for itself at armature 329 and at armature 331 completes the ringing circuit. Ringing current is then intermittently projected over a circuit extending from the generator V' by way of back contact and armature 317, back contact and armature 292, armature 331 and its front contact, wiper 352, bank contact 362 and then over the line circuit of the called subscriber at substation A', bank contact 360 engaged by the wiper 350 and the said wiper, back contact and armature 289, armature 315 and its back contact, upper winding of the ring cut off relay 280, front contact and armature 330 and through the winding of the rotary magnet 294 to battery. When the called subscriber answers the ring cut off relay 280 energizes over the line circuit and completes the talking connection 55 at the same time opening the above traced ringing circuit. It will be understood of course that the rotary magnet 294, while it is included in the circuit of the ring cut off relay 280, does not receive enough current to energize. The back bridge relay 276 will be energized over the line circuit of the called subscriber at substation A', and will operate at armatures 300 and 301 to reverse the battery back over the line of the calling subscriber at substation A. Upon operating, relay 276 completes a circuit of the slow acting relay 277 in an obvious manner at armature 294. Upon energizing, the latter relay establishes a locking circuit for itself 60 65 70 75 80 85 90 95 100 105 110 115 120 125 130

at armature 304 and at armature 303 opens the normal circuit to the line relay 278 but because of the operation of the back bridge relay 278 this circuit has already been 5 opened and therefore this operation will have no function at this time. When the battery is reversed over the calling subscriber's line loop, current will flow in the same direction in both windings of the polarized relay 201 which will therefore operate. Upon operating relay 201 at armature 213 breaks the locking circuit of the slow acting relay 200 and at the front contact of this armature places ground on the wiper 237 10 and at armature 212 opens the circuit of the switching relay 202. The ground is placed on wiper 237 over the following circuit: Ground by way of armature 224 and its back contact, and armature 213 and its front contact. This ground extends by way of wiper 237, bank contact 242, conductor 254, and 15 through the winding of the slow acting relay 265 to battery. This latter relay energizes, establishes a locking circuit for itself 20 at armature 267 and at armatures 266 and 268 places the called subscriber in connection with the conference holding trunk comprising conductors 251 and 255. The line relay 278 of the switch H' is maintained 25 operated by the high impedance bridge 206 across the conductors of the holding trunk. Upon deenergizing, the relay 202 again completes the circuit of the line relay 203 which 30 energizes over the line circuit placing ground on the release trunk conductor 258 at armature 222. It will be noticed that the line relay 203 at armature 224 breaks a point in the locking circuit of relay 200; this provision is made so that upon the relay 201 deenergizing, as it will immediately following 35 the deenergization of relay 202, the relay 200 will not again lock itself before it has deenergized. It will be understood that the line relay 203 energized before the slow 40 acting relay 200 has had time to deenergize and thus ground is maintained on the release trunk conductor 258 and on the holding 45 trunk conductors 57 and 252.

Upon energizing, relay 203 at armature 50 224 also completes a circuit which includes the switching relay 202 and the stepping magnet 207 in series and at armature 223 connects the test wiper 236 to the above circuit at a point midway between the switching relay and the said stepping magnet. Ground will now be present on test contact 55 241 engaged by the test wiper 236 and the switching relay 202 will therefore be short circuited and the stepping magnet 207 being supplied with direct ground by way of the 60 said test wiper will operate as a buzzer to advance the switch wipers step by step in search of an idle trunk line. When this is found there will be no ground present on 65 the test contact engaged by the test wiper 236

and the switching relay 202 being no longer short circuited will energize in series with the stepping magnet 207. Upon energizing, the switching relay 202 operates as before to extend the line of the calling subscriber 70 to the line relay of the selected connector switch. Relay 204 will be again energized in series with the line circuit. The line relay of the connector so seized will also be energized and will operate to complete the 75 circuit of its associated slow acting release relay. This latter relay will operate in the usual manner to establish a holding locking circuit for the switching relay 202 of the 80 rotary switch F.

The calling subscriber may now operate his calling device in accordance with the digits of the next desired subscriber's number. The line relay of the connector so seized will operate in response to these digits to control the operation of the vertical magnet in stepping the wipers opposite the level of bank contacts in which is located the contacts associated with the desired subscriber's line. A series of interruptions 85 is each time produced in the circuit of the series relay 204 which operates to close the circuit of the slow acting relay 205. Relay 205 energizes and at armatures 230 and 233 90 opens the inductive connection to the first called subscriber thereby preventing him from receiving any of the dialled impulses sent by the calling party which would otherwise cause him some annoyance. By the operation of the slow acting relay 205, 95 relay 200 is again energized the latter relay operating to place ground on the holding and release trunk conductor at armature 210 and to establish a locking circuit 100 for itself at armature 211.

When the calling device is operated for the first digit of the subscriber's number the relay 204 in the rotary switch F and the line relay of the last seized connector switch are energized and deenergized in 110 response thereto. As before, the operation of the relay 204 has no function at this time. The line relay of the connector switch however in actuating, controls the operation of 115 its associated rotary magnet in rotating the switch wipers into engagement with the bank contacts associated with the line of the next subscriber desired. The slow acting relay in the seized switch similar to relay 282 energizes in series with the rotary 120 magnet and operates to connect the test wiper to the test relay similar to 283. The operation of the seized connector switch now depends upon whether or not the line 125 associated with the set of bank contacts with which the wipers are in engagement is or is not busy. If busy, a ground potential will be present upon the test contact engaged by the test wiper and the test relay will be energized. Upon energizing, 130

the test relay establishes a locking circuit for itself and places the busy tone on the line of the calling subscriber. The calling subscriber upon hearing this tone will replace his receiver upon the switchhook thereby initiating the release of its last connector switch. But the switches F, H, and C, are maintained operated as before described, also the connector H' will be maintained operated because the relay 265 has established a locking circuit for itself to ground on release or holding trunk conductor 252 by way of armature 267. It will therefore be seen that only the connector switch last used is restored to normal and all the other connections are maintained. Thus, this provision will enable the calling subscriber to release only the last connection and maintain all the others.

It will now be assumed that the line of the last named desired subscriber was idle when connection was attempted therewith. Under these conditions the switching relay similar to relay 284 in the associated connector switch will be energized and will operate to close the ringing circuit. Ringing current will now be intermittently applied to the line of the called substation until the subscriber thereat responds. When this occurs a circuit will be completed for the ring cut off relay which will energize, stopping the ringing and completing the circuit to the back bridge relay. The back bridge relay of this connector will now operate to reverse the battery over the calling subscriber's line. The polarized relay 201 in the switch F will be again energized and will operate as before described to break the locking circuit of relay 200, to open the circuit of the switching relay 202 and to energize the relay similar to relay 265 in the last operated connector switch. This latter relay will energize placing the second called subscriber onto the conference holding trunk comprising the conductors 56 and 58 and at the same time locking itself to ground on the release or holding trunk conductor 57. The rotary switch F will then operate in the manner described hereinbefore to select another trunk line terminating in an idle connector switch.

In the same manner as above described the calling subscriber may call the next subscriber desired in the conference and so on. When the last connection has been established the connector used in this connection will operate to reverse the battery over the calling subscriber's line thereby operating the polarized relay 201 and causing the switch F to select another idle trunk in the manner described before. The relay 201 also causes the energization of the trunk relay similar to the relay 265 thereby shifting the last subscriber into connection with the conference holding trunk. Conversation may

now take place between the calling and all the called subscribers over the heavy talking conductors.

Should any one of the subscribers in the conference desire to retire therefrom at any time before the calling subscriber hangs up he may do so simply by replacing his receiver upon the switchhook. For the purposes of description it will be assumed that the subscriber at substation A' desires to retire from the conference. When the receiver is replaced at this substation back bridge relay 276 of the associated connector H' will deenergize thereby restoring the normal connections of the line relay with regard to the conference holding trunk conductors 251 and 255. As before mentioned, the slow acting relay 277 at armature 303 opens the normal connections of the line relay to the incoming trunk line. Therefore when the back bridge relay 276 deenergizes the line relay will also deenergize and initiate the release of the connector H' in the usual manner.

When the conference is terminated the calling subscriber at substation A will replace his receiver upon the switchhook thereby causing the deenergization of the line relay in the connector switch last selected. Ground is therefore removed from the release trunk conductor thus opening the holding circuit of the switching relay 202 which deenergizes removing ground from the release trunk conductors 258, 252 and 57. The switches F, H, and C, also restore to normal in the usual manner as there is no holding circuit for the relays 15, 100, and 109. When ground is removed from the release trunk conductors 252 and 57 the locking circuits of the trunk relays similar to relay 265 is opened and each relay thus deenergizes. The line relays of the operated connector switches will deenergize but the connectors will maintain their operated position until the called subscriber hangs up as the release magnet circuit of each operated switch is maintained opened by the associated back bridge relay similar to relay 276. During this interval before the called subscribers have hung up, ground is maintained on each of the release trunk conductors. The circuit by which this is accomplished will be described with regard to the connector H' as all the connector switches are identical with this one. It extends from ground G²⁰, by way of armature 307 and its back contact, armature 302 and its front contact, back contact and armature 304, to release trunk conductor 253. When the called subscribers replace their receivers upon the switchhook the back bridge relay in each of the associated connector switches deenergizes completing the release magnet circuit in a manner hereinbefore described. All the apparatus used in the conference is now restored

to normal.

Having described how a conference is established between a number of subscribers the manner in which an ordinary local connection is set up will now be explained. For this purpose it will be assumed that the subscriber at substation A desires to call the subscriber at substation A'. The calling subscriber will therefore remove his receiver and operate his calling device in accordance with the digits of the number assigned to the subscriber at substation A'. When the receiver is removed at substation A the line switch C individual thereto operates in the usual manner to select an idle trunk line terminating in an idle connector switch. It will be assumed that the connector H was idle at this time and was selected for use.

When the calling subscriber operates his calling device for the first digit of the desired number a series of interruptions are produced in the circuit of the line relay 103 which deenergizes a corresponding number of times. A series of impulses are thereby sent over the following path: ground G', armature 129 and its back contact, armature 125 and its back contact, armature 116 and its back contact, armature 134 and its front contact, off normal springs 156 and 157, winding of the series relay 106 and through the winding of the vertical magnet 110 to battery. The above is the circuit over which the first vertical impulse is transmitted. Upon the first vertical step of the switch the off normal springs are shifted and the remaining impulses to the vertical magnet traverse a different circuit which is the same as the one previously traced, except that it includes the off normal springs 156 and 158 and armature 141 and its front contact, the slow acting relay 106 being now in operated position. The magnet 110 operates to raise the wipers 160-162, inclusive, step by step until they are placed opposite the level of bank contacts in which is terminated the desired subscriber's line. The slow acting relay 106 is energized in series with the vertical magnet and maintains its armature attracted throughout the vertical movement of the switch and at the end of the vertical operation deenergizes transferring the operating circuit of the connector H to the rotary magnet 111.

The calling subscriber may now operate his calling device in accordance with the last digit of his number. The line relay 103 operates in response thereto to send a corresponding number of impulses to the rotary magnet 111 in series with the slow acting relay 107. Magnet 111 operates to rotate the switch wipers step by step until they are placed in engagement with the set of contacts associated with the desired subscriber's line which we will assume, are the set of contacts 171-173, inclusive, associated with the line of the substation A'. The slow

acting relay 107 is energized in series with the rotary magnet and upon operating connects the test wiper to the test relay 108. The further operation of the switch depends upon whether or not the line of the subscriber at substation A is busy or idle. If busy a ground potential will be present on the test contact 172 and a circuit will be completed for the test relay 108. Upon operating, this latter relay places the busy tone on the calling subscriber's line and establishes a locking circuit for itself. The calling subscriber upon hearing this tone will replace his receiver thereby releasing the switches H and C in the usual manner.

It will be assumed, however, in the present case that the line of the subscriber at substation A' was idle when the connector H attempted to connect thereto. Under these circumstances there will be no ground potential upon the test contact 172 and the test relay 108 will not energize. Then, following the deenergization of the slow acting relay 107 a circuit is completed for the switching relay 109 extending from ground on release trunk conductor 73 by way of armature 147 and its back contact, lower winding of the switching relay 109, back contact and armature 143, test wiper 161, test contact 172, private normal conductor 69, winding of the switching relay 43 and the winding of the stepping magnet 45 of the line switch C' to battery. Relays 109 and 43 operate over this circuit. However, due to a mechanical interlocking device controlled by the line relay 44 the switching relay 43 of the line switch C' operates only enough to disconnect the line conductors of the substation A' from their normal battery and ground connections. The switching relay 109 upon energizing, establishes a locking circuit for itself at armature 152 and at armature 154 completes the ringing circuit. Ringing current is then intermittently applied to the line of the subscriber at substation A' until the subscriber thereat answers. When the receiver is removed at the called substation, the ring cut off relay 105 energizes, opens the ringing circuit, and completes the talking connection. The back bridge relay 101 energizes over the called subscriber's line, operates to reverse the battery to the calling subscriber, and to complete the circuit of the slow acting relay 102 which energizes and locks. Conversation may now take place between the two subscribers over the heavy talking conductors. Battery being supplied to the calling subscriber from the windings of the line relay 103 and to the called subscriber from the windings of the back bridge relay 101.

When the conversation is terminated the calling subscriber will replace his receiver upon the switchhook thereby opening the circuit of the line relay 103 which deener-

gizes opening the circuit of the slow acting release relay 104. Upon the deenergization of relay 104 the line switch C releases and the circuit of the slow acting relay 102 is opened. If the called subscriber keeps his receiver off the hook following the deenergization of the slow acting relay 102 ground is again placed on the release trunk conductor 73 to prevent the connector H from being again seized until the called subscriber has replaced his receiver. When the receiver is replaced at the called substation, the back bridge relay 101 deenergizes causing the release of the connector. Should the called subscriber have replaced his receiver upon the switchhook before the calling subscriber, the back bridge relay 101 would de-energize. The circuit of the line relay is then opened at armature 124 and thereafter the connector H is released. All the foregoing operations take place in a manner fully described hereinbefore.

Having fully described and ascertained the features of my invention what I consider to be new and desire to have protected by Letters Patent will be pointed out in the appended claims.

What I claim as my invention is:

1. In an automatic telephone system, means controlled by a calling subscriber for connecting with a called line, means including a reoperative switch for then extending the connection to a plurality of other called lines, each time maintaining the last established connection, and means whereby the subscriber on one of said called lines can disconnect his line from said connection.

2. In an automatic telephone system, means controlled by a calling subscriber for connecting with a called line, means including a reoperative switch for then extending the connection to a plurality of other called lines, while the receiver at the calling substation is maintained off the switchhook, each time maintaining the last established connection, and means whereby the subscriber on one of said called lines can disconnect his line from said connection.

3. In an automatic telephone system, means controlled by a calling subscriber for connecting with a called line, means including a reoperative switch for then extending the connection to a plurality of other called lines, each time maintaining the last established connection, and means whereby the subscriber on one of said called lines can disconnect his line without disturbing the connection between the other lines.

4. In an automatic telephone system, means controlled by a calling subscriber for connecting with a called line, means including a reoperative switch for then extending the connection to a plurality of other called lines while the receiver at the calling substation is maintained off the switchhook,

each time maintaining the last established connection, and means whereby the subscriber on one of said called lines can disconnect his line without disturbing the connection between the other lines.

5. In an automatic telephone system, means controlled by a calling subscriber for connecting with a called line, means including a reoperative switch for then extending the connection to a plurality of other called lines, each time maintaining the last established connection, and means whereby the subscriber on the first called line can disconnect his line without disturbing the extended connection.

6. In an automatic telephone system, means controlled by a calling subscriber for connecting with a called line and then extending the connection to a plurality of other called lines, each time maintaining the last established connection, and means whereby said calling subscriber may disconnect his line without disturbing the extended connection.

7. In a telephone system, a calling subscriber's line, a holding trunk, a plurality of called subscribers' lines adapted to be associated therewith, and means whereby a subscriber on said calling line may successively connect all of the said plurality of called subscribers' lines with said holding trunk, said means comprising a like number of automatic switches intervening between the said holding trunk and the called line in each case.

8. In a telephone system, a calling subscriber's line, a holding trunk, a plurality of called subscribers' lines adapted to be associated therewith, and means whereby a subscriber on said calling line may successively connect all of the said plurality of called subscribers' lines with said holding trunk while the receiver at the said calling substation is maintained off the switchhook, said means comprising a like number of automatic switches intervening between the said holding trunk and the called line in each case.

9. In a telephone system, calling and called subscribers' lines, automatic switches, a trunk line terminating in each of said switches, means whereby a subscriber on one of said calling lines may establish a connection with one of said called lines through a series of said trunk lines and automatic switches, a holding trunk, and means controlled by the response of the subscriber on the connected called line for placing his line into connection with said holding trunk.

10. In a telephone system, calling and called subscribers' lines, automatic switches, a trunk line terminating in each of said switches, a holding trunk, means whereby a subscriber on one of said calling lines may set up a plurality of connections with a num-

- ber of said trunk lines and called lines by way of said automatic switches, and means controlled by the response of the subscriber on each called line for placing the said line in connection with the said holding trunk.
5. 11. In a telephone system, calling and called subscribers' lines, automatic switches, a holding trunk, means whereby the subscriber on one of said calling lines may successively establish a plurality of connections with a plurality of said called lines, said means including circuit arrangements for operating one of said switches as many times as there are connections established, 10 and means whereby a local connection is maintained between the said called lines by way of said holding trunk.
11. In a telephone system, calling and called subscribers' lines, automatic switches, a holding trunk, means whereby the subscriber on one of said calling lines may successively establish a plurality of connections with a plurality of said called lines, said means including circuit arrangements for operating one of said switches as many 15 times as there are connections established, and means whereby a local connection is maintained between the said called lines by way of said holding trunk.
12. In a telephone system, calling and called subscribers' lines, automatic switches, a holding trunk, means whereby the subscriber on one of said calling lines may successively establish a plurality of connections with a plurality of said called lines, and means whereby a local connection is 20 maintained between the said called lines by way of said holding trunk after the subscriber on the said calling line has replaced his receiver upon the switchhook.
13. In a telephone system, a calling subscriber's line, a holding trunk, two automatic connector switches, one of said switches accessible to the other, a called subscriber's line accessible from either connector switch, means whereby the subscriber on 25 the said calling line may establish a connection with the said called line directly from said first automatic switch, means whereby the subscriber on said calling line may establish a second connection with the said 30 called line by way of both connector switches, a relay, means for energizing said relay upon the response of the subscriber on the said called line in the second connection, and means controlled by said relay for extending 35 the said called line into connection with the said holding trunk.
14. In a telephone system, a calling subscriber's line, automatic switches, a holding trunk, a plurality of called lines adapted to 40 be associated therewith, means under the control of the subscriber on the said calling line for establishing successively a connection with each of said called lines, a relay, means for energizing said relay upon the 45 response of the subscriber on each of said called lines, and means controlled by said relay in each case for connecting the answering called lines together on said holding trunk.
15. In a telephone system, a calling subscriber's line, automatic switches, a holding trunk, a plurality of called lines adapted to 50 be associated therewith, means under the control of the subscriber on the said calling line for establishing successively a connection 55 with each of said called lines, relays, contacts on said relays connected to said holding trunk in multiple, and means for energizing one of said relays upon the response of the subscriber on each one of said called 60 lines for connecting the said called lines to the holding trunk.
16. In a telephone system, a calling subscriber's line, automatic switches, a holding trunk, a plurality of called lines adapted to 65 be associated therewith, means under the control of the subscriber on said calling line for establishing successively a connection with each of said called lines, relays, means for energizing one of said relays upon the 70 response of the subscriber on each one of said called lines, means controlled by each relay to connect the associated called line to the holding trunk, and means for maintaining each of said relays energized to maintain the associated called line in connection with said holding trunk after the subscriber on the said calling line hangs up.
17. In a telephone system, a group of connectors, an automatic hunting switch having access to said connectors, means including said hunting switch and one of said connectors for extending a connection to a called line, and means controlled by the response of the called subscriber for causing 75 said hunting switch to select and connect with another of said connectors.
18. In a telephone system, automatic switching mechanism responsive to the dialing of a plurality of telephone numbers in 80 immediate succession one after the other, and by the same calling subscriber, for connecting the stations corresponding to such numbers together, said switching mechanism comprising a group of connectors having access to the called stations, an automatic hunting switch, and circuit arrangements effective each time after a connector connects up 85 a called station for operating said hunting switch to select another connector for use 90 by the calling party in connecting up the next called station.
19. In a telephone system, automatic switching mechanism responsive to the dialing of a plurality of telephone numbers in 95 immediate succession one after the other, and by the same calling subscriber, for connecting the stations corresponding to such numbers together, said switching mechanism comprising a group of connectors having access to said called stations, an automatic hunting switch, and means for operating said hunting switch between the calling of every 100 two consecutive telephone numbers for 105 selecting a different connector for use by the calling subscriber.
20. In a telephone system, a connector, a trunk line terminating in said connector, automatic switches having access to said connector over two different paths, means for 110
- 115
- 120
- 125
- 130

operating one of said switches for seizing said connector and extending a connection to a called line, and relay means operated upon response of the subscriber on said called line only when said connector is seized over a certain one of said paths, to complete a connection to said called line over said trunk line.

21. In a telephone system, a connector, a trunk line terminating in said connector, automatic switches having access to said connector over two different paths, means for operating one of said switches for seizing said connector and extending a connection to a called line, and relay means operated upon response of the subscriber on said called line only when said connector is seized over a certain one of said paths to complete a connection to said called line over said trunk line, said relay means being inoperative when said connector is seized over the alternative path.

22. In a telephone system, a connector, a trunk line terminating in said connector and provided for establishing a plurality of simultaneous talking connections thereover, automatic switches, said connector being accessible to said switches over two different paths, means for operating one of said switches for seizing said connector and extending a connection to a called line, and relay means operated upon response of the subscriber on said called line only when said connector is seized over a certain one of said paths, to complete a connection to said called line over said trunk line.

23. In a telephone system, a trunk line, said trunk line terminating in a plurality of connectors and provided to serve a plurality of simultaneous talking connections, certain ones of said connectors being accessible over two different paths, means for seizing one of said connectors and extending a connection to a called line, and relay means individual to said connector and operated upon response of the subscriber on said called line only when said connector is seized over a certain one of said paths, to complete a connection to said called line over said trunk line.

24. In a telephone system, a trunk line, said trunk line terminating in a plurality of connectors and provided to serve a plurality of simultaneous talking connections, certain ones of said connectors being accessible over two different paths, means for seizing one of said connectors and extending a connection to a called line, and relay means individual to said connector and operated upon response of the subscriber on said called line only when said connector is seized over a certain one of said paths, to complete a connection to said called line over said trunk line, said relay means being inoperative when

said connector is seized over the alternative path.

25. In a telephone system, a trunk line arranged to serve a plurality of simultaneous talking connections, a connector switch having access to called lines under numeric control of a calling line, and having access to said trunk line over a certain level, means for seizing and for operating said connector to said level, automatic hunting means effective when said connector is operated to said level, to provide for further numeric selection of a called line, and relay means operated upon response of the subscriber on said called line to complete a connection to said called line over said trunk line.

26. In a telephone system, the method of connecting more than two subscribers in a simultaneous talking connection by means of a connector which ordinarily serves for two party connections, consisting in operating said connector to a certain level to seize a trunk line, and operating a relay upon the response of the subscriber on a called line to complete a connection over said trunk line.

27. In a telephone system, the method of connecting more than two subscribers in a simultaneous talking connection by means of a connector which is accessible to automatic switches over two different paths and having a trunk line terminating therein, consisting in operating said connector into engagement with a called line, and operating a relay upon the response of the subscriber on said called line to complete a connection over said trunk line only when said connector is seized over a certain one of said paths.

28. In a telephone system, the method of connecting a plurality of subscribers' lines in simultaneous talking relation over a trunk line terminating in a plurality of connectors, certain of said connectors being accessible over two different paths, consisting in operating one of said connectors to extend a connection to a called line, and operating a relay, individual to said connector, upon response of the subscriber on said called line only when said connector is seized over a certain one of said paths.

29. In a telephone system, a completed connection extending from a calling line to a called line and including a plurality of switches and trunk sections, means in one of said switches controlled from the called line for interrupting said connection, other switches, and means for re-operating said switch into engagement with one of said other switches for extending said calling line into connection with another called line.

30. In a telephone system, a completed connection extending from a calling line to a called line and including a plurality of

- switches and trunk sections, means in one of said switches controlled from the called line for interrupting said connection, other switches, and means for re-operating said switch into engagement with one of said other switches for extending said calling line into connection with another called line without releasing said first called line.
31. In a telephone system, a completed connection extending from a calling line to a called line and including a plurality of switches and trunk sections, means in one of said switches controlled from the called line for interrupting said connection, other switches, means for re-operating said switch into engagement with said other switches to extend said calling line to a plurality of called lines, successively and under control of said calling line.
32. In a telephone system, a completed connection extending from a calling line to a called line and including a plurality of switches and trunk sections, means in one of said switches controlled from the called line for interrupting said connection, other switches, means for re-operating said switch into engagement with said other switches to extend said calling line to a plurality of called lines, successively and under control of said calling line without releasing said first called line.
33. In a telephone system, a completed connection extending from a calling line to a called line and including a plurality of switches and trunk sections, means in one of said switches controlled from the called line for interrupting said connection, other switches, means for re-operating said switch into engagement with said other switches to extend said calling line to a plurality of called lines successively and under control of said calling line without releasing said first called line, and means for connecting said calling line into talking relation with said called lines.
34. In a telephone system, a completed connection extending from a calling line to a called line and including a plurality of switches and trunk sections, means in one of said switches controlled from the called line for interrupting said connection, other switches, means for re-operating said switch into engagement with said other switches to extend said calling line to a plurality of called lines successively and under control of said calling line without releasing said first called line, and means for connecting said calling line in talking relation with said called lines after said calling line has established connection with the last called line.
35. In a telephone system, a calling line, a first called line, a plurality of trunk sections and switches controlled from said calling line successively to extend a connection to said first called line, other called lines accessible from one of said switches, means in said switch controlled from said first called line for interrupting said connection, and switching means co-operating with said switch to extend said calling line into connection with other called lines under control of said calling line.
36. In a telephone system, a calling line, a first called line, a plurality of trunk sections and switches controlled from said calling line successively to extend a connection to said first called line, other called lines accessible from one of said switches, means in said switch controlled from said first called line for interrupting said connection, and switching means controlled by said calling line and co-operating with said switch to extend said calling line into connection with other called lines without releasing said first called line.
37. In a telephone system, a calling line, a first called line, a plurality of trunk sections and switches controlled from said calling line successively to extend a connection to said first called line, other called lines accessible from an intermediate one of said switches, means in said switch controlled from said first called line for interrupting said connection, and means controlled by said calling line and co-operating with said switch for extending said calling line into connection with a plurality of other called lines without releasing said first called line, said switch being provided with means to establish talking connection with said first called line when said calling line has completed the connection to the last called line.
38. In a telephone system, the method of connecting a plurality of lines into simultaneous talking relation, consisting in the operation of an automatic switch which is included in a train of switches connecting a calling line with a called line, and the operation of a relay controlled from the called line to interrupt said train at said switch and to cause said switch to establish connection with a plurality of other called lines under control of the calling line.
39. In a telephone system, the method of connecting a plurality of lines into simultaneous talking relation, consisting in the operation of an automatic switch which is included in a train of switches connecting a calling line with a called line, and the operation of a relay controlled from the called line to interrupt said train at said switch and to cause said switch to establish connection with other called lines under control of the calling line without releasing the called line.

Signed by me at Chicago, Illinois, this 20th day of January 1921.

JOHN E. GARDNER.
